DETONATION BLOCK FUZE MOUNT

Donald E. Smith, Kingsville, Md., assignor to the United States of America as represented by the Secretary of the Army

Filed Apr. 2, 1963, Ser. No. 270,124

9 Claims. (Cl. 102—49)

(Granted under Title 35, U.S. Code (1952), sec. 266)

The invention described herein may be manufactured and used by or for the Government of the United States of America for governmental purposes without the payment to me of any royalty thereon.

This invention relates to a mechanical arrangement for severing the casing of a missile warhead to release a chemical agent payload.

It make use of a detonation block fuze mount which propagates the initial explosive impulse furnished by a fuze to ignite a plurality of conventional explosive detonating cords. The mentioned fuze may be of any well known type that has a predetermined time setting means to emanate a flash. A suitable fuze of this kind for example is the standard U.S. Army mechanical time fuze, M-421, presently utilized in the chemical warhead section for the U.S. Army surface to surface Littlejohn Rocket and chemical warhead section for the U.S. Army, surface to surface Honest John Rocket.

The detonating cord may consist of any well known type such as for example is described in a prior patent to Ortynsky et al., No. 2,809,583.

Reference will now be made to the accompanying drawing which illustrates an example of construction according to the invention and in which:

FIG. 1 is a perspective view of the invention.

FIG. 2 is an exploded perspective view of the invention.

FIG. 3 is a perspective fragmentary embodiment of a cam and a fuze shown in locked position.

FIG. 4 is a perspective fragmentary embodiment of a cam and a fuze, shown in an unlocked position.

FIG. 5 is a perspective view of the missile warhead.

Referring more particularly to FIGS. 1 and 2 of the drawing, the detonation fuze mount generally made of metal as frusto-conical body 1 which is designed to fit and to be fastened in the nose cone section of a chemical agent filled missile 3 (see FIG. 5). The body 1 has in it, a centrally located and fastened fuze supporting block 5 having an engagement key 7. The fuze supporting block has a central hole 9 containing a tetryl pellet 11 over which is placed a felt spacer 13. The hole has near the bottom a plurality of radially extended communicating passageways 15, while cut through its entire width it has a pair of radially extended communicating channels or slots 17. Each of the passageways 15 receives a soft aluminum ferrule 19 containing a substantially long conventional detonating cord 21, shown in FIG. 5. The end of the cords at the stems of the ferrules are left slightly protruding in order for them to attain positive contact with the tetryl pellet. The stems of the ferrules are left slightly protruding in order for them to attain positive contact with the tetryl pellet. The stems are crimped about the cords preventing the latter's withdrawal. If desired the ferrules may be omitted and the cords firmly cemented inside of the passageways. The other ends of the detonating cords are fed downward through holes 23 into the lower end portion of the missile warhead 3 where they are firmly secured (by means not shown). Each of the channels 17 receives a relatively short strand of detonating cord (not shown).

The fuze supporting block 5 has fastened on the top surface through means of screws 25, a retaining clip 27. The general configuration of this clip is substantially the

2

same as that of fuze supporting block 5. The clip having a pair of flash holes 29 aligning with the channels 17, and a key-way 31 to engage the key 7, is provided with a plurality of forked prongs 33 and a curved bracket 35. The prongs serve the purpose of holding the ferrules 19 in place, while the curved bracket engages a beveled flange 37 of a fuze 39 (see FIGS. 3 and 4). The body 1 has mounted next to the supporting block 5 through means of set screws 41, a cam support 43 which houses in cavity 45, an expansion spring 47. The cam support has on the top surface a pivotal cam 49 having a beveled camming edge 51 and hook-shaped handle 53 welded thereon which serves as means for the rotation of said cam. The cam together with the handle, the cam support, and the expansion spring are held together by means of a bolt 55. The expansion spring is retained on the bolt through means of a washer 57 and a nut 59. The end of the bolt (having the washer and the nut) terminates in an over-sized well 61. The cylindrical body 1 is fitted and fastened onto the missile warhead through means of a plurality of bolts (not shown) which pass through holes 63 located inside of cut-outs 65.

At assembly stage, the fuze 39 is placed (by the operator) on the top surface of the retaining clip 27. The bottom of the fuze engages the key 7 while the beveled flange 37 engages the curved bracket 35. The operator rotates the cam 49 (through means of the handle 53) in a clockwise direction. This action brings the camming edge 51 into contact with the beveled flange 37 forcing the latter to lock within the bracket 35 (see FIG. 3). To release the fuze, the operator rotates the cam counter-clockwise (see FIG. 4) this action freeing the fuze for removal.

The sequence of events that occur for proper functioning of the invention are as follows:

A hand operated spring biased cam secures the M-421 fuze in proper position on the clip by orientation to accept the key.

Upon a pre-determined time setting, a flash emanates from the M-421 fuze. This flash detonates the detonating cords 21 by means of the detonation block fuze mount.

Since the M-421 fuze consists of two timers used in parallel for reliability, either of two flash tubes in the fuze cam initiate first. Accordingly, either of the two short strands of detonating cord will carry the explosive impulse to the central tetryl pellet. Ignition of this pellet simultaneously ignites the plurality of detonating cords which extend down the length of the missile warhead and thus severs the casing.

It is envisioned that this concept can be successfully adapted and utilized in any application wherein an explosive impulse from a fuze is required to propagate ignition to any type detonating cord configuration.

While certain representative embodiments and details have been shown for the purpose of illustrating the invention, it will be apparent to those skilled in this art that various changes and modifications may be made therein without departing from the spirit and scope of the invention.

I claim:

1. In a chemical agent filled guided missile warhead having a separable nose cone coextensive with an outer casing, and a flanged fuze means having a plurality of flash tubes; a detonation block fuze mount comprising the combination of:

- (a) frusto-conical body means mounted in said nose cone;
- (b) fuze supporting block means centerally mounted on the forward face of said frusto-conical body means and having a central hole, a plurality of radial slots extending outwardly from said hole and a plu-

- rality of passageways extending from said hole to the outer surfaces of said block means, said slots being in communication with said flash tubes of said fuze means;
- (c) retaining clip means attached to the forward surface of said block means, said clip means having curved bracket means adapted to fit said flanged fuze means thereon and having a plurality of flash holes therein in communication with said flash tubes of said fuze means;
- (d) cam means having handle means thereon pivotally mounted on the forward face of said frusto-conical body means spaced from said block means whereby upon rotation of said handle means said fuze means is secured in place between said cam means and said curved bracket means.
2. A chemical agent filled guided missile warhead as set forth in claim 1 in which the flange of said fuze means is a frusto-conical flange.
3. A chemical agent filled guided missile warhead as set forth in claim 2 in which said cam means comprises a semi-circular disk with a beveled camming edge.
4. A chemical agent filled guided missile warhead as set forth in claim 1 in which said fuze means has two flash tubes and said block means has three passageways.
5. In a chemical agent filled guided missile warhead having a nose cone, an outer casing, and a flanged fuze means having a plurality of flash tubes, a detonation block fuze mount comprising the combination of:
- (a) frusto-conical body means mounted in said nose cone;
- (b) fuze supporting block means centrally mounted on the forward face of said frusto-conical body means and having a central hole, a plurality of radial slots extending outwardly from said hole and a plurality of passageways extending radially from said hole to the outer surfaces of said block means, said slots

- being in communication with said flash tubes of said fuze means;
- (c) retaining clip means attached to the forward surface of said block means, said clip means having curved bracket means adapted to fit said flanged fuze means thereon and having a plurality of flash holes therein in communication with said flash tubes of said fuze means;
- (d) cam means having handle means thereon pivotally mounted on the forward face of said frusto-conical body means spaced from said block means whereby upon rotation of said handle means said fuze means is secured in place between said cam means and said curved bracket means;
- (e) detonating means extending lengthwise of said warhead adjacent the inner surface of said outer casing and extending through said passageways, said central hole and said radial slots whereby upon the flashing of said timer, the detonating means will cause a splitting of said warhead into a plurality of sections which releases the chemical agent payload.
6. A chemical agent filled guided missile warhead as set forth in claim 5 in which the flange of said fuze means is a frusto-conical flange.
7. A chemical agent filled guided missile warhead as set forth in claim 6 in which said cam means comprises a semi-circular disk with a beveled camming edge.
8. A chemical agent filled guided missile warhead as set forth in claim 5 in which said fuze means has two flash tubes and said block means has three passageways.
9. A chemical agent filled guided missile warhead as set forth in claim 5 in which the detonating means comprises detonating cord adjacent said outer casing, in said passageways, and in said radial slots, and a detonating pellet in said central hole.
